UNITED STATES PATENT OFFICE

2,078,789

SPINNING SPINDLE

Sven R. Bergman, Nahant, Mass., assignor to
General Electric Company, a corporation of
New York

Application December 8, 1933, Serial No. 701,478

4 Claims. (Cl. 248—26)

My invention relates to a mounting for securing spinning spindles to a spinning frame.

At certain speeds called critical speeds the spindle shaft is distorted from the axis of rotation by centrifugal force and, while rotating in the distorted position, causes severe vibrating forces to be transmitted to the bearings in which the shaft rotates. The speeds at which the critical speeds occur depend upon the stiffness of the shaft, the inertia of the rotating and stationary parts, and the character of the mounting which is used to secure the spindle to the spinning frame. Since it is not feasible to operate a spinning spindle at a speed low enough to avoid any critical speeds and, since the severe vibration caused at a critical speed renders the spindle unsafe for operating at that speed, it is necessary to choose the normal running range of the spindle so that it occurs between two of the critical speeds of the shaft and to resiliently mount the spindle to lessen the strain on the bearings caused by the vibrations while the shaft is passing through a critical speed.

An object of my invention is to provide an improved and simplified mounting for fastening a spinning spindle to a spinning frame.

Another object of my invention is to provide an improved mounting for resiliently securing a spinning spindle to a spinning frame in which the critical speeds of the spindle are widely separated to provide a wide speed range between the second and third critical speeds thereof.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing in which Fig. 1 is a perspective view of a mounting embodying my invention applied to a motor-driven spindle for spinning artificial silk or the like; Fig. 2 is an enlarged sectional view of the mounting shown in Fig. 1; and Fig. 3 is an enlarged sectional view of a preferred form of the mounting.

I have shown my invention in Figs. 1 and 2 as applied to a motor-driven spindle for spinning artificial silk in which an electric motor having an outer casing 1 drives a vertical spindle shaft 2 carried in suitable guide and thrust bearings in the casing. The spindle shaft extends above the motor casing and has a spinning device or the like, such as a bucket 3 mounted on the upper end.

The mounting for resiliently fastening the spindle to the spinning frame consists of concentric inner and outer members having rubber or other resilient material secured therebetween. The members are secured respectively to the spindle and to the spinning frame. The outer member is in the form of a cylindrical ring 4 attached to the lower end or base of the motor casing by bolts 5, thereby providing a cup-shaped enclosure on the lower portion of the motor casing. The inner member 6 which acts as a supporting member is secured to the spinning frame 7 by means of a nut 8 threaded on the supporting member 6. An annulus of rubber or other resilient material 11 is secured between the opposed walls of members 4 and 6. Parts 4 and 6 of the mounting are concentric with the spindle shaft 2 and have opposed walls extending along and parallel to the axis of the shaft. The resilience of the mounting is obtained from the rubber which is secured between the parts 4 and 6 of the mounting. The rubber is preferably placed between the opposed walls of parts 4 and 6 in an uncured state and vulcanized in position while subject to pressure acting on the exposed edges of the rubber. The pressure causes the rubber to flow and fill depressions 12 in each of the parts of the mounting to assist in holding the rubber in place. By this method of assembly, the rubber, although not actually bonded to the opposed walls, is secured between each of the walls so that there is no movement between the surface of the rubber and the adjacent wall to cause wear on the rubber or to allow turning of the motor casing with respect to the supporting member. The exposed edges 13 of the rubber may be coated with an oil or acid-resistant varnish or other suitable coating which will prevent deterioration of the rubber. However, due to the shielding effect of the outer part 4 of the mounting, the rubber is well protected without the varnish coating.

Turning of the spindle mounting in the spinning frame is prevented by a washer 9 clamped between the frame 7 and nut 8. Pins 10 on the washer which fit in corresponding holes in the frame resist any force tending to twist the spindle in the frame.

With the mounting at the base of the motor, the force due to the first and second critical speeds of the spindle shaft produce a rocking or pivoting of the motor about an axis near the base of the motor and perpendicular to the axis of the shaft. These forces are cushioned by a shearing action of the rubber between the parts 4 and 6 of the mounting. The resulting movement of

part 4 tends to prevent the transmission of these forces to the bearings in which the shaft is carried. Since the mounting is relatively elastic to rocking forces, the first and second critical speeds occur at lower speeds than would be the case if the mounting were relatively rigid to rocking forces. The forces due to the third critical speed of the shaft tend to cause radial movement of the part 6 with respect to the part 4. This mounting is relatively rigid to forces radial to the axis of the shaft, since the forces in this direction cause compression of the rubber between the members 4 and 6, and rubber is relatively rigid in compression. Rigidity in a radial direction is a desirable characteristic of the mounting since the third critical speed of the shaft is thereby caused to occur at a higher speed, and the operating range between the second and third critical speeds is increased. With this type of mounting, it is possible to vary the resistance to rocking forces, thereby adjusting the second critical speed of the shaft, without substantially affecting the resistance to radial forces with the consequent changing of the third critical speed. It is desirable that the mounting be located at the base or lower end of the motor since a mounting which is relatively elastic to rocking forces and relatively rigid to radial forces when so placed widens the range between the second and third critical speeds of the spindle shaft.

In Fig. 3 I have shown a preferred form of my invention. The outer part of this mounting comprises a ring 14 secured to the base of the motor casing 1 by means of bolts 15, thereby providing a cup-shaped enclosure on the lower portion of the motor casing. The inner part of the mounting which acts as the supporting member consists of parts 16 and 17 which are secured together by rivets 18 and by a bolt 19. A nut 8 cooperating with threads on the member 16 secures the mounting to the spindle frame 7 as in the construction shown in Fig. 1. The outer and inner members 14, and 16 and 17 respectively, have substantially parallel opposed walls concentric with and extending along the axis of the spindle shaft and flaring outwardly therefrom to form a double taper. The walls are preferably of wedge-shaped configuration, as shown in the drawing. An annulus of rubber 20, secured between the opposed walls of member 14 and members 16 and 17, provides the cushioning action of the mounting. The mounting may be assembled by placing a strip of rubber in the uncured state between parts 14 and 16, securing part 17 to part 16 by means of bolt 19 and rivets 18, and vulcanizing the rubber in position while subject to pressure acting on the exposed edges 21. The exposed edges 21 of the rubber may be coated with a protective varnish. The action of this mounting is similar to that of the mounting shown in Fig. 2, except that the forces which tend to rock the motor are resisted by combined shear and fibre stress of the rubber 20. I find that by varying the angle of taper in the opposed walls of the mounting, the resistance to the rocking forces produced by vibration of the spindle may readily be changed without substantially affecting the resistance offered by the mounting to radial forces. The resistance to the rocking forces may also be varied by changing the thickness of the rubber.

In the foregoing description reference is made to the first, second, and third critical speeds of

the spindle shaft. In referring to these critical speeds of the spindle shaft, it will be understood that I mean the spindle shaft in the system including the spinning bucket 3 mounted on the shaft, the motor rotor mounted on the shaft, and the stator 1, all of which are carried by the rubber mounting indicated at 11 or 20.

Although I have shown a particular embodiment of my invention, I do not desire to be limited to the construction described, and I intend in the appended claims to cover all modifications which do not depart from the spirit and scope of my invention.

What I claim as new and desire to secure by Letters Patent of the United States, is:

1. A mounting for an electric motor having a vertical spindle shaft extending therefrom comprising a ring concentric with the axis of the shaft secured to the base of the motor and cooperating therewith to form a cup-shaped enclosure, a supporting member concentric with the axis of the shaft and extending within said ring, said ring and said supporting member having opposed walls extending along the axis of the shaft, resilient material arranged within said cup-shaped enclosure and secured between said opposed walls, and means for fastening said supporting member to a spinning frame or the like.

2. A mounting for an electric motor having a vertical spindle shaft extending therefrom comprising a ring concentric with the axis of the shaft secured to the base of the motor and cooperating therewith to form a cup-shaped enclosure, a supporting member concentric with the axis of said shaft and extending within said ring, said ring and said supporting member having substantially parallel opposed walls of double frusto-conical configuration, resilient material arranged within said cup-shaped enclosure and secured between said opposed walls, and means for fastening said supporting member to a spinning frame or the like.

3. A mounting for an electric motor having a vertical spindle shaft extending therefrom comprising a ring concentric with the axis of the shaft secured to the base of the motor and cooperating therewith to form a cup-shaped enclosure, a supporting member concentric with the axis of the shaft and extending within said ring, said ring and said supporting member having substantially parallel opposed walls of wedge-shaped configuration extending along the axis of the shaft, resilient material arranged within said cup-shaped enclosure and secured between said opposed walls, and means for fastening said supporting member to a spinning frame or the like.

4. A mounting for an electric motor having a vertical spindle shaft extending therefrom comprising a ring concentric with the axis of the shaft secured to the base of the motor and cooperating therewith to form a cup-shaped enclosure, a supporting member concentric with the axis of the shaft and extending within said ring, said ring and said supporting member having substantially parallel opposed walls extending along the axis of the shaft, having a double taper from the axis of the shaft, resilient material arranged within said cup-shaped enclosure and secured between said opposed walls, and means for fastening said supporting member to a spinning frame or the like.

SVEN R. BERGMAN.
